[57] CLAIM

The ornamental design for a fur trimmed eye glass case,
as shown and described.

DESCRIPTION

FIG. 1 is a front elevational view of a fur trimmed eye
glass case showing my new design;

FIG. 2 is a rear elevational view thereof;

FIG. 3 is a right side elevational view thereof, the left
side being a mirror image of the side shown;

FIG. 4 is a top plan view thereof;

FIG. 5 is a bottom plan view thereof; and

FIG. 6 is an inside elevational view thereof in open
form.

FIG. 1

FIG. 2

FIG. 3

FIG. 4

FIG. 5

FIG. 6
